UNITED STATES PATENT OFFICE.

FREDERICK A. BRENNER, OF MILWAUKEE, WISCONSIN.

LEATHER-SPLITTING MACHINE.

Application filed March 17, 1926. Serial No. 95,312.

This invention relates to flexible rolls for leather splitting machines and refers more particularly to what is known in the art as ring rolls, each including a plurality of relatively narrow cylinders or rings arranged upon a shaft in such a manner as to restrict longitudinal movement of the ring members but permit them to assume positions either concentric or eccentric with relation to the shaft.

Numerous complicated methods have been devised by which the ring roll is enabled to adjust itself to the varying thickness of the leather and to accommodate for any irregularities in the surface thereof, and this invention has for one of its objects the provision of an improved ring roll which is extremely simple in construction and which functions in a highly suitable manner.

Another object of this invention is the provision of means for securing the ring members against longitudinal shifting on the shaft and so located as to be beyond the sphere of the deteriorating influences of the acids resident in the leather at the time of splitting. This feature particularly adapts my ring roll for use with chrome leather, as the chrome acid contained therein is extremely destructive to the present type of roll commonly employed.

A further object of this invention resides in the provision of ring members of equal diameters having apertures of different diameters, and co-operating spacer members likewise of differing diameters, the difference between the diameters of adjacent apertures and adjacent spacers facilitating the securing of the ring members against longitudinal movement on the shaft.

A still further object of this invention resides in the provision of rings having spacers so designed that replacement of the rings or the spacers may be easily accomplished.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention con-

structed according to the best mode I have so far devised for the practical application of the principles thereof, and in which:

Figure 1 is a cross-sectional view taken through a leather splitting machine equipped with my improved roll;

Figure 2 is a sectional view taken through Figure 1 on the plane of the line 2--2, illustrating how variations in the thickness of the leather affects the position of the rings, and

Figure 3 is a perspective view of one end of the ring roll, some of the rings being separated from the rest to more clearly illustrate the construction thereof.

Referring now more particularly to the accompanying drawing in which like numerals designate like parts throughout the several views, 5 is an adjustably fixed roll positioned adjacent a knife 6 and as is usual in machines of this kind, the roll and knife are adjustable with respect to each other, both horizontally and vertically, but as this adjustment, and the means for obtaining it forms no part of this invention, the same has not been shown.

An auxiliary pressure roll 7 engages the top of the roll 5, and mounted below the roll 5 is another roll 8 which is commonly called a ring roll and, as before described, is composed of a plurality of ring members 9 arranged in juxtaposition and together forming the continuous cylindrical surface of the roll 8. Frictionally engaging the periphery of the ring roll is a drive roll 10 having an outer layer formed of a yieldable substance such as rubber or the like, and positioned so as to urge the ring roll towards the fixed roll, especially during the operation of the machine.

The leather L or other material to be split is fed along a fed table 11 to be engaged between the fixed roll and the ring roll and forced onto the knife to split the same. As this process of splitting leather is well known in the art, further detail description thereof is deemed unnecessary except to say that due to the varied thickness of a hide or leather to be split it is evident that only one of the split portions can have a uniform thickness, which in most instances is that portion emerging from above the knife or between it and the fixed roll, the desired thickness thereof being obtained by the vertical adjustment of the fixed roll.

The description will now be directed to

the construction of the ring roll in which this invention is centered. As above stated the ring roll is composed of a plurality of relatively narrow discs or rings 9 which together form the roll 8, the rings being divided into two groups or sets, one set having relatively large apertures 12 and the other having apertures 13 of smaller diameters, the individual rings being arranged alternately with respect to their aperture diameters.

Cooperating with and inserted in the apertures of the rings is a plurality of spacer members 14 and 15, the outside diameters of which are likewise varied, the larger spacers 14 being inserted in the apertures 12 and the smaller spacers 15 in the apertures 13. The entire plurality of spacers with their respective rings surrounding them are mounted on a shaft 16 and are secured against longitudinal movement thereon by a nut 17 threaded on each end of the shaft 16. The shaft with the spacer members secured thereon by the clamping action of the nuts 17, substantially forms a solid mass, and still retains the separate spacer members loosely fitted to the shaft.

It will be noted that the apertures 12 and 13 are considerably larger than the diameters of their respective spacers 14 and 15, thereby permitting the ring members 9 to assume positions either concentric or eccentric with relation to the shaft, to accommodate the various thicknesses of the leather and its numerous projections or irregularities, see Figure 2. Furthermore the difference between apertures and their respective spacers is constant so that when all of the ring members will still form one continuous roll.

In order to permit the ring members to freely adjust themselves to the varying conditions the thickness of the individual spacer member is slightly greater than its associated ring member, preferably a few thousandths of an inch, thereby providing ample play between alternate spacer members to allow the ring member mounted therebetween to function properly.

It will also be seen that the diameters of the apertures and the spacers are so proportioned that longitudinal movement of the rings along the spacer members is impossible; and furthermore the spacers are separate members secured to the shaft by clamping nuts threaded on its ends thus preventing all freezing thereof onto the shaft, an objection found in constructions where the spacers are secured onto the shaft by set screws. The splitting of chrome leather invariably freezes the set screws to the parts in the former type of device, due to the action of the tanning acids on the metal, making it extremely hard to remove the spacer members.

From the foregoing description taken in connection with the accompanying drawing, it will be readily apparent to those skilled in the art to which an invention of this character appertains that I provide a ring roll for leather splitting machines which will function efficiently and, at the same time, be of simple construction and permit the ready disassembling of the roll for repairs.

What I claim as my invention is:

1. A device of the class described, comprising a shaft, a plurality of apertured ring members mounted on the shaft, said ring members being of equal outside diameter and having their apertures alternately large and small, and a second plurality of ring members mounted on the shaft within the apertures of said first-mentioned ring members.

2. A device of the class described, comprising a shaft, a plurality of apertured ring members mounted on the shaft, said ring members having their apertures substantially of the same diameter as the shaft and of alternately large and small outside diameter, and a second plurality of apertured ring members of equal outside diameter and alternately large and small apertures, mounted on the first-mentioned ring members.

3. A device of the class described, comprising a shaft, a spacer member of relatively small diameter mounted on the shaft, an apertured ring member surrounding the spacer member and having its aperture substantially greater than the diameter of the spacer member, a second spacer member having a diameter greater than that of the ring member aperture mounted on the shaft and abutting the first-mentioned spacer member, and a second apertured ring member surrounding the second-mentioned spacer member and having its aperture substantially greater than the diameter of said spacer member.

4. In a device of the class described, a shaft, a plurality of spacer members of varying diameters mounted on said shaft, and a plurality of apertured ring members cooperating with the spacer members whereby the ring members are held against longitudinal movement on the shaft but are free to assume concentric or eccentric positions with relation to the shaft.

5. In a device of the class described, a shaft, a plurality of spacer members of varying diameters mounted on the shaft, a plurality of apertured ring members cooperating with the spacer members whereby the ring members are free to assume concentric and eccentric positions with relation to the shaft, and means for securing the spacer members and the ring members against longitudinal movement on the shaft,

said means being located adjacent the ends of the shaft.

6. In a device of the class described, a shaft, a plurality of spacer members of varying diameters mounted on the shaft, a plurality of apertured ring members co-operating with the spacer members whereby the ring members are free to assume con-

centric and eccentric positions with relation to the shaft, and means located at the ends of the shaft for securing the spacer members to the shaft whereby the shaft and spacer members substantially form a solid mass.

In testimony whereof I affix my signature.

FREDERICK A. BRENNER.
